UNITED STATES PATENT OFFICE.

WILLIAM E. VINCENT, OF PORT DEPOSIT, MARYLAND, ASSIGNOR TO
REYNOLDS BROTHERS, OF SAME PLACE.

CAN-HEADING MACHINE.

SPECIFICATION forming part of Letters Patent No. 274,863, dated March 27, 1883.

Application filed January 25, 1883. (No model.)

To all whom it may concern:

Be it known that I, WILLIAM E. VINCENT, of Port Deposit, in the county of Cecil and State of Maryland, have invented certain Improvements in Can-Heading Machines, of which the following is a specification.

My invention relates to machines for crimping the heads or ends of tin cans upon the bodies, and is especially designed for operating upon cans having a V-shaped groove formed in their bodies parallel with and close to each end.

The invention consists in various features and details of construction, hereinafter explained.

In the accompanying drawings, Figure 1 represents a perspective view of my improved machine from the rear; Fig. 2, a perspective view from the front; Fig. 3, a longitudinal vertical section through the machine, showing a can in position; Fig. 4, an enlarged view, showing the can in the shape in which it is placed in the machine preparatory to being acted upon thereby.

As mentioned, this machine is designed to operate upon cans having a groove or corrugation extending around its body close to each end, as indicated in Fig. 4, such cans having long been used; and the purpose of the machine is to crimp or bend the flanges of the heads or ends of the can down into the grooves or corrugations, both ends being acted upon simultaneously.

Referring now to the drawings, A represents a frame, preferably made of metal, in which are mounted two short shafts or spindles, B and C, directly in line with one another, but separated a distance about equal to the length of the can to be operated upon. The spindle B is shouldered or otherwise held against moving endwise; but spindle C is arranged to slide longitudinally in its bearings, being pressed toward spindle B by a spring, D, bearing against its outer end. Both spindles or shafts are free to rotate in the frame A, and spindle B is furnished with a crank, E, a band-wheel, or other means of imparting rotary motion thereto. Each spindle or shaft B C carries a flat disk, F, slightly smaller in diameter than the heads of the can, and of a form adapted

to fit or conform to the face of the latter, as 50 more plainly indicated in Fig. 3.

The can to be operated upon comes to the machine in the condition represented in Fig. 4, with the corrugations or grooves a formed in its body G, and with the flanged heads b 55 placed upon the body, the flanges c projecting over but above the grooves, as shown. The heads are slightly dished or depressed, as is usual in such cans, and this depression serves to receive the disk F and to prevent the slipping of the can when held between the disks. The cans, in the condition indicated, are placed between the disks, with one head against each, being firmly held in such position by the pressure of spring D, which forces the disk of spindle 60 65 C against the can-head with sufficient pressure not only to insure the firm retention of the can, but also to cause the two disks to turn in unison when motion is imparted to spindle B.

In order that the disks may be readily separated to permit the insertion of a new can or the removal of one that has been operated upon, I provide a lever, H, which is pivoted to a suitable post or support, and has its inner end forked to embrace and enter a grooved collar 70 or boss, d, on the spindle C, the outer end of the lever being connected with a treadle or foot-lever, I, by a cord or chain, J, passing over a pulley, k, in such manner that when the treadle or foot-lever is depressed the lever H will 75 80 be moved horizontally, and in thus moving it draws back the spindle C and its disk against the pressure of the spring D. In this way the disks may be separated by merely pressing with the foot upon the treadle, leaving both 85 hands free to adjust the can, turn the crank, and perform other necessary operations.

The crimping is effected by one or more pair of rollers, L L, two pair being preferably used, one pair mounted upon a rod or bar, e, carried 90 by a spring-arm, M, and the other upon a rod, N, extending across the frame of the machine below the disks. The rod N is employed, whether provided with rolls or not, and serves, in conjunction with a similar rod, O, placed on 95 the opposite side of a vertical plane passing through the axis of spindles B C, to center the can as it is placed in the machine, the rods

being each placed a distance from the axis of the spindles equal to the radius of the cans, or a trifle more. The spring-arm M presses normally toward the axis of spindles B C, and is 5 sufficiently strong to insure a proper crimping action of the rolls carried thereby; and in order that the crimping-rolls may be lifted when inserting or removing a can, I attach a cord or band, f, to said spring and carry it upward 10 over a pulley, and thence through or over suitable guides or pulleys to the treadle or foot-lever I, so that when the latter is depressed it will raise the spring-arm M and rollers L L simultaneously with the withdrawal of spindle 15 C, thus placing the control of these parts under the pressure of the operator's foot. The arm M is preferably made adjustable, being held by a set-screw, j. The rollers L L of rod e, as also those on rod or shaft N, when used 20 thereon, are free to rotate upon the rods, and are pressed toward each other by springs g, which are sufficiently elastic to yield readily and permit the rolls to move outward or apart in case of meeting with any irregularities in 25 the part operated upon, or if required to operate upon a can of slightly greater length than usual. This feature is of great importance, and is essential to a machine designed to operate upon both ends simultaneously.

30 The rollers are of the form indicated in Fig. 3, the flange or lip h being designed to travel on the end face of the head and the beveled portion i to act upon the flange c of the head, as shown.

35 It will be seen that some of the parts may be modified as to their arrangement—as, for instance, by substituting a spiral spring upon the shaft of spindle C for the straight spring shown, by arranging the roller shaft or rod N 40 to rise and fall in guides and providing springs to bear upon its ends, by employing an upright elbow-lever in lieu of the lever H and the cord-guiding pulleys, and in other details that will readily suggest themselves to the machinist or mechanic.

45 If desired, the rod O may also be furnished with crimping-rollers.

I am aware that a socketed disk and a sliding disk have before been used; but such arrangement precludes the simultaneous crimping of 50 both heads, because the edge of one head is covered by the walls of the socket. My ar-

rangement leaves the edges of both heads exposed.

The rods or spindles N and e will ordinarily 55 be held stationary, or prevented from rotating; but they may be permitted to rotate, it being immaterial to the action of the machine which plan is adopted.

Having thus described my invention, what I 60 claim is—

1. In combination with frame A, spindles B C, provided with disks F F, lever H, and spring-arm M, the latter carrying crimping-rollers L L, and both the lever and the spring-arm connected with a treadle or lever, substantially as shown and described.

2. In combination with a can-holder substantially such as described, a spring-arm provided with a rod carrying crimping-rollers 70 adapted to act upon both heads of the can simultaneously.

3. In combination with a can-holder substantially such as described, a rod provided with crimping-rollers to act simultaneously 75 upon opposite ends of the can held by said holder and held normally at a given position upon the rod by spring-pressure, whereby they are permitted to adapt their position to variations or irregularities of the can.

4. In a can-heading machine, the combination of a can-holder, a crimping-roll loosely mounted upon a rod, and a spring arranged to press against the crimping-roll and to sustain it in a given position until pressed back by an 85 uneven projection of the can or its head.

5. In combination with a can-holder substantially such as described, the rod provided with loose crimping-rolls L L, and springs g, all arranged to operate substantially as shown 90 and described.

6. The herein-described can-heading machine, consisting of frame A, spindles B C, carrying disks F F, spring-arm M, carrying rod e, provided with yielding rollers L L, lever H, connected with spindle C, substantially as shown, and treadle or lever I, connected with lever H and spring-arm M, all substantially as shown and described.

WILLIAM E. VINCENT.
